UNITED STATES PATENT OFFICE.

FRANCIS B. CONVERSE, OF BROOKLYN, NEW YORK, ASSIGNOR TO MERGENTHALER LINOTYPE COMPANY, A CORPORATION OF NEW YORK.

LINE-CASTING MACHINE.

1,155,892.

Specification of Letters Patent.

Patented Oct. 5, 1915.

Application filed April 14, 1910. Serial No. 555,521.

To all whom it may concern:

Be it known that I, FRANCIS B. CONVERSE, of the borough of Brooklyn, county of Kings, and State of New York, have invented a new and useful Improvement in Line-Casting Machines, of which the following is a specification.

My invention has reference to a "thermostatic" mechanism controlling the flow of gas to a burner used for heating the melting pot of a line casting or analogous machine. In this class of machines, such, for example, as the well known Mergenthaler "linotype" machine, the body of type metal in a pot must be maintained in a molten condition and at a uniform temperature. When the heat is first applied to the pot containing the solid metal, it must be done gradually and by means of a small flame, as otherwise the small body of molten metal imprisoned between the bottom of the pot and the solid metal above will by its expansion fracture the pot or find its way, under the extreme pressure developed, through the pores of the cast iron. After the melting of the metal has progressed to a certain point, it is desirable to greatly increase the flame or the application of heat, in order to bring the body of the metal to the required temperature without loss of time. After the metal has reached the required temperature, it is necessary to modify the flow of gas from time to time as cold metal is added to the mass, or as the mass is reduced by consumption, the object being to maintain a practically uniform temperature notwithstanding the change in conditions.

To this end my invention consists broadly in a mechanism controlled by the temperature of the metal in the pot, and acting automatically to admit a reduced flow of gas to the burner when the pot is cold; when the pot is heated a gradually increased flow of gas; and later, when the metal is fully melted a diminished flow, sufficient only to maintain the required temperature.

I believe it to be wholly new in the art to construct a thermostatic gas controlling device in such manner that an increase in the temperature causes an increase in the flow of gas. It is also wholly new to construct a thermostatic device in such manner that as the temperature advances it will permit first an increased flow of gas and thereafter a diminished flow,

While I have illustrated in the accompanying drawings a form of mechanism which is well adapted for use under ordinary conditions, it will be understood by the skilled mechanic after a consideration of this specification that the details of the construction may be widely modified without changing the mode or principle of action, or passing beyond the scope of my invention. For purposes of illustration I have shown my device in connection with the melting pot now used in commercial Mergenthaler machines, known to all persons skilled in the art.

Figure 1 is a top plan view of a pot having my gas governor applied thereto. Fig. 2 is a vertical section of the same from front to rear, the governing device being shown in side elevation. Fig. 3 is a vertical section through the governor, the parts in the position they occupy when the pot is cold and when the flame is first started. Fig. 4 is a top plan view of the same. Fig. 5 is a section through the valve mechanism on an enlarged scale, the parts in the position they occupy during the normal action of the machine. Fig. 6 is a vertical section through the valve, the parts in the position occupied when the pot is cold, at the beginning of operations. Fig. 7 is a similar view showing the valve in the position it occupies when the molten metal is at or slightly above the proper temperature. Fig. 8 is a central vertical section of the parts seen in Fig. 7 and in the same position. Fig. 9 is a horizontal section on the plane 9—9 of Fig. 8.

Referring to the drawings, A represents the ordinary melting pot of a Mergenthaler line casting machine, B an ordinary Bunsen burner or gas burner located beneath the pot for the purpose of applying the flame thereto to melt the contained type metal, as usual, C is a pipe through which the gas is supplied to the governor, D is the governor, E is a pipe through which the gas is delivered from the governor to the burner. The governor, which consists mainly of an expansion rod acting through intermediate devices on a compound valve, is constructed as follows: A supporting tube, a, of iron or equivalent metal, is extended through the lid of the pot and downward into the space occupied by the molten metal and secured in place by a screw, b. To the top of this tube is firmly screwed a casting, c, of the form shown. Within the tube there is

loosely seated a long rod, *d*, of aluminum or equivalent material, connected to the tube at its lower end by a pin, *e*. The upper end of the rod carries a hard metal bearing piece, *f*, acting upward against a screw, *g*, in one end of the lever *h*, which is pivoted to the casting *c* at *i*, so that when the parts are subjected to an increased temperature within the pot, the rod *d*, elongating 10 faster than the tube *a*, acts to throw the force of the free end of the lever *h* upward.

The casting *c* has its upper portion enlarged and recessed in such manner as to form an upper chamber, *j*, into which the 15 gas is delivered by the supply pipe *C*, and a lower chamber, *k*, from which the gas is delivered into the pipe *E*, leading to the burner. The controlling valves located between the upper and lower chambers are 20 constructed in the manner shown in Figs. 3, 5, 6 and 7. A tubular valve seat, *l*, flanged at the upper end, is seated tightly within the casing or body *c* and is held down to its place by a spiral spring, *m*, confined in 25 place by an overlying screw, *n*, threaded into the top of the chamber and closing the same. The removal of this screw permits the entire valve mechanism to be withdrawn at the top.

30 Within the valve seat *l* there is a vertically reciprocating valve, *o*, of cylindrical form, having near the opposite ends circumferential grooves, *o*¹ and *o*², connected by a passage, *o*³, passing vertically through the center of the valve; groove *o*¹ connecting that passage *o*³ by a cross-passage *o*³¹, and *o*² connecting that passage *o*³ by a cross-passage *o*³². The proportions of this valve in 35 relation to the length of the seat *l* are such that it has the three following actions: 40 1. When lowered to the position shown in Figs. 3 and 6, its upper end will prevent the passage of gas from the upper chamber *j* into the groove *o*¹. 2. When in an intermediate position, as shown in Figs. 5 and 7, it will permit the gas to flow from the upper chamber *j* into the groove *o*¹, thence through the port *o*³ to the lower groove *o*² into the lower chamber *k*, whence it passes to the 45 burner. 3. When raised sufficiently to carry its lower end within the valve seat *l*, its lower end will close the seat and prevent the escape of the gas, which has entered from above, into the lower chamber. The 50 valve *o* is urged constantly downward by a spiral spring, *p*, and at the lower end the valve rests upon a thin diaphragm, *s*, closing the lower side of the chamber *k*, and resting in turn upon a stud on the end of 55 the lever *h*.

As will presently appear, the foregoing parts serve to deliver the gas in large quantity to the burner, and to diminish the flow when the temperature approaches the maximum limit. It is necessary, however, that 60

a minimum supply of gas shall be furnished to the burner before the above parts begin their action, while the pot is cold and the metal in a solid state. To this end I provide the valve *o* from the upper end downward with a small port or opening, *q*, leading into the port *o*³. The port *q* is formed centrally in a screw nipple bearing that reference, this rendering the port removable and interchangeable. When the valve 70 stands in the initial position shown in Figs. 3 and 6, closing the upper end of the seat *l*, a moderate supply of gas entering from the upper chamber through the small port *q* will continue downward through passage *o*³ 80 to the lower groove *o*², thence downward into chamber *k* and to the burner. This is the condition of the parts when the flame is first lighted, and when it is necessary to apply a moderate heat beneath the pot. As 85 the body of the metal increases in temperature and approaches or reaches a molten condition, the elongation of the rod *d* lifts the lever *h*, which in turn raises the diaphragm and the valve *o* until the latter assumes the position shown in Fig. 5, thus 90 allowing the maximum flow of gas through the valve to the burner, causing a rapid increase in the temperature of the metal. When the temperature of the metal reaches 95 or exceeds the proper limit, the continued elongation of the rod lifts the valve *o* above its intermediate position, so that its lower end contracts the gas outlet, as shown in Fig. 7, permitting the passage of only a 100 sufficient amount of the gas to maintain the temperature at the required point. If, therefore, there is a failure to replenish the pot with metal as the contents are reduced 105 by consumption, the flame will be diminished and excessive temperature prevented. If, on the other hand, cold metal is supplied to the pot and the temperature of the mass therein reduced, the rod contracts and 110 the flame is instantly increased to maintain the temperature. If from any cause an excessive temperature is momentarily reached, the flame is diminished to permit a fall in temperature.

As type metals differ in composition and 115 in diffusion of temperature, the screw *g* is provided as a compensating or adjusting device, between the actuating rod and lever, so that by turning the screw the governor 120 may be adjusted to regulate the flow of gas and the temperature with due regard to the character of the metal being used.

It will be observed that my governor has 125 a triple or three stage action, delivering as it does first a small supply of gas, thereafter a largely increased supply, and finally and under normal conditions a medium supply, subject to a moderate variation as changes in temperature demand. It will be, of course, understood that the rod *d* and its 130

inclosing tube constitute a mechanical thermostat, and that they may be replaced by any equivalent thermostatic devices adapted to impart motion to a heat-controlling device, such as the valve described.

As is well understood in the art and for that reason not illustrated, I may supplement the burner B shown herein by a small pilot burner supplied by gas or other fuel from any source whatsoever, for maintaining sufficient flame at the burner to cause it to re-light if by any possibility, such as the excessive elevation of valve σ , it temporarily becomes extinguished. The valve may be so designed or constructed that when its outlet end is close against its seat there will nevertheless exist a small opening to allow just enough gas through to maintain a small flame in the burners.

As a matter of terminology the valve device described, may be said to have three "ports". The valve port q is a constant gas inlet port for the valve. When the groove σ^1 is in use, as in Figs. 5, 7, 8, there is a space between valve and seat through which gas or other fuel or heating means flows into the groove; and this space, which is marked v , may be considered as a variable inlet port. Likewise as to groove σ^2 , there is a space, marked w , which is a variable outlet port. The actuation of the valve varies ports v and w , while port q is constant. These features in an automatic heat-controlling valve are new. In a sense the terms inlet and outlet as just used are relative and interchangeable; for, since there are no back-pressure valves shown, the port areas alone determine flow, so that the gas could obviously be reversed in direction, the pipe E coming from a main and the pipe C leading to the burner; and such a reversal is intended to be covered herein. Initially the constant inlet port q and variable outlet w are open, and a convenient predetermined minimum gas flow enables the burner to be started with a small heating effect. As the type metal heats up the variable inlet v in time opens thus supplementing the gas supply and increasing the heat. When the full operation is reached and the metal temperature is at a predetermined normal high temperature, differing with different metals and in no case a fixed or exact temperature but one having some latitude, then this is uniformly maintained by or through the variations in the degree of closure of the outlet valve port w , the inlet v being wide open. Excess temperature further closes w thus causing a reversal of the valve's previous action.

Gas, it will be understood, is only the preferred example of sources of heat that could be employed in my device, it being only essential that an increased or varying action of the heating means is producible and

controllable by a thermostat, and the valve is only the preferred form of heat-controlling device therefor.

Having thus described my invention, what I claim is:

1. In combination, the seat τ , the valve σ sliding within said seat and adapted to reciprocate longitudinally therein, said valve being formed with circumferential grooves σ^1 , σ^2 , each adapted to be closed or opened according to the relation between the valve and seat, and said valve also having the longitudinal central passage connecting the grooves σ^1 and σ^2 , and a thermostat for longitudinally moving the valve. 70

2. In combination, the seat τ , the valve σ sliding within said seat and adapted to reciprocate longitudinally therein, said valve being formed with circumferential grooves σ^1 and σ^2 , each adapted to be closed or opened according to the relation between the valve and seat, and said valve also having the longitudinal central passage connecting the grooves σ^1 and σ^2 , and a thermostat for longitudinally moving the valve, said 75 central passage extending to the gas supply end of the valve for admitting a constant initial gas supply. 80

3. In a fuel governor, a valve device comprising a seat or throat τ and a valve σ adapted to slide longitudinally therein, said valve having inlet port or groove σ^1 and outlet port or groove σ^2 near its opposite ends respectively, with a passage connecting said inlet and outlet, and an inlet q at one end of said valve, said inlet q also connected to the inlet σ^1 and outlet σ^2 , and means for reciprocating said valve. 95

4. A thermostatically-actuated heat-controlling valve having a variable outlet port (as w), a variable inlet port (as v), and a constant inlet port (as q), said valve adapted initially to have said outlet and constant inlet open, and adapted when in full operation at predetermined high temperature to uniformly maintain such temperature by the variable degree of closure of said outlet while the variable inlet is wide open. 105

5. A thermostatically-actuated heat-controlling valve having a variable outlet port (as w), a variable inlet port (as v), and a constant inlet port (as q), said valve adapted initially to have said outlet and constant inlet open and variable inlet closed, and adapted after a rise of temperature to have the variable inlet become open for an increased heat supply, and adapted when in full operation at predetermined high temperature to uniformly maintain such temperature by the variable degree of closure of said outlet while the variable inlet is wide open. 115

6. In a thermostatic governor, the combination with the thermostat and a fuel supply of a fuel valve device operated by the 120

thermostat to maintain proper temperature, said valve device comprising a seat, a movable valve in sliding contact within said seat, a fuel supply chamber to one side of the valve and delivery chamber to the other side, said valve provided with a flange adapted to vary the fuel flow from supply to delivery chamber, and provided with internal passages for conducting fuel from supply

to delivery chamber when said flange is 10 closed.

In testimony whereof I hereunto set my hand this eleventh day of February, 1910, in the presence of two attesting witnesses.

FRANCIS B. CONVERSE.
